UNITED STATES PATENT OFFICE.

GEORGE L. JENKINS, OF PHILADELPHIA, PENNSYLVANIA, ASSIGNOR TO
THE AUSTIN, NICHOLS & COMPANY, OF NEW YORK, N. Y.

DESIGN FOR A BOTTLE.

SPECIFICATION forming part of Design No. 26,065, dated September 22, 1896.

Application filed June 19, 1896. Serial No. 596,217. Term of patent 14 years.

To all whom it may concern:

Be it known that I, GEORGE L. JENKINS, a citizen of the United States, residing at Philadelphia and State of Pennsylvania, have invented and produced a new and original Design for Bottles, of which the following is a specification.

In the accompanying drawings I have illustrated the design.

Figure 1 is an elevation of a bottle, showing my improved design; and Fig. 2 is a sectional view thereof. Fig. 3 is a sectional view on the line 3-3 of Fig. 1.

The leading feature of my design consists of a bottle having its body portion tapering from about a central point toward the bottom on a slight taper and curving upwardly to form the neck on curved lines and terminating in an outwardly-flaring lip.

The lip of the bottle is shown at *a* and the neck at *b*, and this neck merges into the body by a gradual flaring outwardly, providing a bottle without a distinct shoulder, and from the enlarged part of the bottle there is a gradual tapering to the bottom, the body being joined to the bottom without a foot, so as to make a plain connection. The bottom is made slightly flaring.

I claim—

A design for a bottle herein shown and described.

In testimony whereof I affix my signature in presence of two witnesses.

GEORGE L. JENKINS.

Witnesses:

GEO. H. BURGIN,
G. ERNEST PIXTON.
